UNITED STATES PATENT OFFICE.

HARMER DENNEY, OF BROOKLYN, NEW YORK.

TAG-MAKING MACHINE.

SPECIFICATION forming part of Letters Patent No. 334,220, dated January 12, 1886.

Application filed September 18, 1884. Serial No. 143,395. (No model.)

To all whom it may concern:

Be it known that I, HARMER DENNEY, of Brooklyn, in the county of Kings and State of New York, have invented a new and Improved Tag-Making Machine, of which the following is a full, clear, and exact description.

The object of my invention is to provide a new and improved machine for printing, cutting, perforating, and eyeletting shipping-tags.

10 The invention will first be described in connection with the drawings, and then pointed out in the claims.

Reference is to be had to the accompanying drawings, forming part of this specification, in which similar letters of reference indicate corresponding parts in all the figures.

Figure 1 is a side view of my improved tag-making machine, parts being broken away. Fig. 2 is a side view of the paper-feeding device. Fig. 3 is a sectional plan view of the machine. Fig. 4 is a plan view of the platform over which the paper passes. Figs. 5 and 6 are cross-sectional elevations of the machine, showing the parts in different positions.

25 Fig. 7 is a detail sectional view of the eyeletting mechanism. Fig. 8 is a detail view of the perforating mechanism. Fig. 9 is a detail view of the cutting mechanism. Fig. 10 is a detail sectional view. Fig. 11 is a detail view showing the mechanism for operating the vertically-sliding carriage. Fig. 12 is a plan view of cutter with its movable arm thrown back.

The frame A of the machine is provided at the rear end with two upwardly-inclined arms, 35 A', in which a frame, B, is pivoted to swing up and down.

The type B', for printing the paper C, has to pass over the table or platform A², formed on the frame of the machine.

40 The inking mechanism, the arrangement of the type, &c., are all of the usual construction, and need not be further described.

The main driving-shaft D, journaled in the uprights of the frame A, is provided at one 45 end with a belt-pulley, D', and with a fly-wheel, D², and on the opposite end with a pinion, D³, engaging with a cog-wheel, E', on a shaft, E, provided with a crank, E², and having mounted on its opposite end a wheel, C', 50 connected by means of a connecting-rod, A³, with the swinging or rocking frame B, also connected by a rod, A³, with the wheel E',

whereby the said swinging frame is moved up and down, and the type are pressed on the paper on the bed A², and are raised to permit 55 the inking-rollers to pass over them, which inking-rollers are operated by a connecting-rod, A⁴, pivoted to the frame A and to a rocking part, A⁵, on the rocking frame B.

On the driving-shaft D a bevel cog-wheel, 60 d, is mounted, which engages with a bevel cog-wheel, d', mounted rigidly on the lower end of a shaft, d², pivoted to turn in a piece, d³, held to rock on the shaft D, and containing the wheel d'.

65 On the upper end of the shaft d², between the arms e¹ of the bracket e¹, is mounted the bevel cog-wheel e, which engages with the bevel cog-wheel e' on the end of the shaft of one of the inking-rollers, which is journaled 70 in the bracket e¹, as shown in Fig. 10. The shaft d² is keyed in the neck e² of the bevel cog-wheel e in such a manner that when the frame B rocks the neck can slide up and down on the shaft, and at the same time the neck 75 and its bevel cog-wheel are revolved by the said shaft d². The swinging piece d³, in which the lower end of the shaft d² is journaled, permits the rocking of the said frame.

80 By the above arrangement some of the ink-spreading rollers in the frame B are operated from the main driving-shaft D. The paper is passed over a roller, a, in the frame A, then over a roller, b, above which a circularly-ribbed friction feed-roller, F, is journaled. On 85 one end of the shaft of the roller b a wheel, F', is mounted, with which a pawl, F², engages, pivoted on a swinging frame, F³, connected by a connecting-rod, F⁴, with the cog-wheel E'. The lower end of the rod F⁴ is so arranged and 90 provided with devices as to permit of its adjustment, so that the stroke of the said rod F⁴ can be varied, and the feed thus regulated.

95 On the table A², formed on the frame A, suitable guides, G and G', are provided for guiding the paper straight through the machine. The pin E¹ of the crank E² passes through a lever, H, pivoted to rock on the main shaft D at H', as shown in Figs. 3 and 11. The lever H is provided on its swinging end 100 with a roller, H², which is held in the cavity in the lower end of a vertically-movable carriage, I, connected with a wedge, I', formed at the upper end of the carriage I.

- On the frame of the machine a transversely-sliding carriage, J, is held, which is provided with a horizontal slot, J', through which the paper strip C can pass. On the said carriage 5 a roller, J⁵, is pivoted in such a manner that it can be acted on by the wedge I'. A powerful spring, J², is secured to the carriage J and to the frame A, and draws the carriage J in the direction of the arrow a', Fig. 3.
- On the carriage J an inclined arm, K, is held, on the upper end of which a box, K', for containing eyelets, is secured, from which eyelets box a track, K², runs down on the bar K, and terminates at its lower end in a point, K³, provided with a spring, K⁴, for preventing the eyelets from slipping off.
- On the carriage J a vertically-sliding bar, L, is arranged directly below the lower end of the track K², upon the upper end of which bar 20 L a punch, L', is held, which slides in a vertical guide-tube, L², held by a binding-screw and a boss or projection, L³, to the carriage J, the top of the guide-tube L² projecting slightly above the bottom edge of the slot J' 25 in the carriage. Directly above the said guide-tube a vertical tubular guide or die, L⁴, is held in a boss, projection, or bracket, M, formed on the front surface of the carriage J above the slot J', the bottom edge of the tube L⁴ being flush with the top edge of the slot J'. An elbow-lever, N, pivoted in the frame of the machine, has one end connected with the lower end of the vertically-movable bar L, and on the other end a roller is secured, which 30 rests against a cam-wheel, N', having a projection, N², the said cam-wheel being mounted on a shaft, O, operated by the beveled pinions O' and O² on the shafts E and O. A spring, w, pulls the bar L downward.
- In the upper end of the vertically-sliding carriage I a tube or upsetting-punch, P, is secured, through which a rod, P', is adapted to slide vertically, and directly above the said tube a die, P², is held in the boss or projection M of the carriage J, the said die P² being provided on its lower end with a nipple, P³, the die P² and its nipple P³ projecting slightly below the top edge of the slot J', and being arranged in such a manner that the upper end of the rod P' can come in contact with the nipple. The tube serves as a punch. An L-shaped piece, Q, is held on one side of the boss or bracket M in such a manner that its lower end is below the die P², the said lower end being provided with a slot, through which the nipple P³ can pass. The angle-piece Q is adapted to slide vertically, and is pressed downward by a spring, Q', secured to the front of the carriage and resting on the upper end of the piece Q.
- From the frame of the machine a bracket, Q³, projects, for a purpose that will be set forth hereinafter.
- On the outer end of the shaft O a wheel, 65 R, is mounted, which is provided in its inner side with a cam-groove, in which a roller runs, which is mounted on one end of a lever, R',

pivoted in the frame, the said lever having its opposite end connected by a connecting-rod, R², with a bar, S, provided at its opposite end with an eye mounted on the bolt T', with the eye of a bar, T², to which a fixed blade, T, is attached, and against which a blade, S², secured on the bar S, cuts.

In front of the bar T² of the fixed blade T 75 a support or bed, U, is arranged, which also has an eye mounted on the pivot or bolt T', the said support resting on a rubber cushion, W, on a bracket, W', on the bar T². The bar S is arranged between the bar T² of the fixed 80 blade T and the support U. At their free ends the fixed blade T and the support U form a V-shaped recess, m, corresponding to a V-shaped blade, S², secured on the bottom edge of the bar S.

The operation is as follows: The paper is wound on a drum, n, held to revolve in the forked arms o, projecting from the support. The paper C passes from the drum n over suitable rollers, then between the roller b and 90 the feed-roller F, and is then carried forward by the same, and is printed, while resting on the bed A², by the type on the swinging frame B. The printed paper is then carried forward and passes through the slot J' in the carriage 95 J. The cam-wheel N' revolves, and its projection N², acting on the bell-crank lever N, forces the bar L upward, whereby the punch L', guided in the tube L², is forced up into the die L⁴, thereby punching a hole in the 100 paper. While this is being accomplished the parts are in the position shown in Fig. 6. The rocking lever H now forces up the carriage I, and as the wedge I' comes in contact with the roller J⁵ on the carriage 105 J the said carriage is moved in the inverse direction of the arrow a', whereby the punch L and its guide will be shifted from under that part of the paper that has just been perforated, the parts having the position 110 shown in Fig. 5. Then, when the carriage I, which continues to be acted on by the lever H, rises sufficiently, the upper projecting end of the rod P' in the tube P is passed through the eyelet t in the lower end of the track K², 115 whereby the eyelet is lifted from the track and held on the upper end of the rod P' of the tube P. The carriage I continues to move upward, the roller J⁵ sliding along the straight edge of the wedge I', and as the carriage I 120 moves upward the tube P is moved upward and carries the eyelet t through the aperture made by the punch L'. The top edge of the eyelet strikes the bottom end of the die P², and is upset and clamped on the paper in the 125 usual manner. The spring Q presses down the paper and presses the eyelet off of the nipple P³ of the die P². Then the carriage I slides downward, and the spring J² pulls it in the direction of the arrow a', whereby the 130 punch L' is again brought into position under the die L⁴, and the above operation can be repeated at the proper time. The rod P', which has been forced downward by coming in con-

tact with the nipple P^3 is forced upward, as the carriage I descends, by its lower end striking against the bracket Q^3 . The eyelets in the track K^2 slide down automatically as soon as 5 the last one is removed, so that the rod P' can catch a fresh one. After the paper has been eyeleted it passes under the blade S' , which has been raised, and when the paper is in the proper position the cam R acts on the lever R' in such a manner as to force the knives S' and S^2 downward, whereby the knife S^2 cuts a 10 triangular piece out of one edge of the strip of paper midway between two eyelets, for the purpose of forming the beveled corners of the tags at each side of the eyelet. As the triangular knife S^2 projects slightly below the knife S' , the support U must be made yielding, so as to allow the knife S' to be forced down sufficiently to cut straight across the 15 paper to the apex of the triangular cut. For this purpose I have provided the rubber cushion W , which permits the support U to be forced down a sufficient distance to complete the cut, but immediately forces the support upward after the cut has been made.

In my improved machine the tags are printed, punched, eyeleted, cut off, and their corners beveled all automatically. A ratchet-wheel, d^5 , is provided with a tooth, d^4 , adapted to act on a hammer, e' , adjacent to a bell, e . The ratchet-wheel d^5 is revolved by a pawl, i , operated by a suitable cam on the wheel C' . Every time the wheel C' makes one revolution one tag is completed, and the wheel d^5 is 30 shifted the distance of one tooth for every revolution of the wheel C' . The hammer e' is forced from the bell e , and in snapping back sounds the bell, the signal being given every 35 time there are as many tags completed as there are teeth on the wheel d^5 , and this number is preferably one hundred or one hundred and forty-four, or one gross, so that a signal will be given every time a gross of tags is completed.

45 To permit of adjusting the machine to make tags of different widths, the frame is provided with longitudinal slots, to permit shifting the carriage J a greater or less distance from the cutting device.

50 Having thus described my invention, what I claim as new, and desire to secure by Letters Patent, is—

1. In a tag-making machine, the combination, with the frame, of a driving-shaft, an arm 55 mounted on the driving-shaft and on a crank of a shaft adjacent to the driving-shaft and operated from the same, a vertically-movable carriage actuated by the said arm, and devices, substantially as described, for eyeleting 60 the tags mounted on said carriage, substantially as herein shown and described.

2. In a tag-making machine, the combination, with a frame, of a vertically-movable carriage carrying an upsetting-punch, a transversely-movable carriage carrying a die, and means, substantially as described, whereby the 65 said transversely-movable carriage is moved

by the vertically-movable carriage, substantially as herein shown and described.

3. In a tag-making machine, the combination, with the frame, of a vertically-movable carriage carrying an upsetting-punch, a transversely-movable carriage carrying a die and provided with a roller, and a wedge upon the vertically-movable carriage acting on the said roller, and thereby shifting the transversely-movable carriage, substantially as herein shown and described.

4. In a tag-making machine, the combination, with a frame, of a vertically-movable carriage provided with a wedge and carrying an upsetting-punch, a transversely-movable carriage carrying a die and provided with a roller, which transversely-movable carriage is moved in one direction by the action of the wedge on the roller, and of a spring secured to the transversely-movable carriage and to the frame, which spring moves the transversely-movable carriage in the inverse direction of that in which it is moved by the wedge, substantially as herein shown and described.

5. In a tag-making machine, the combination, with a vertically-movable carriage carrying an upsetting-punch, of a transversely-movable carriage carrying two dies, and of a 95 punch below one of the dies, substantially as herein shown and described.

6. In a tag-making machine, the combination, with a vertically-movable carriage carrying an upsetting-punch, of a transversely-movable carriage carrying two dies, a punch below one of the dies, and an inclined guide-track, at the upper end of which a box containing eyelets is held, substantially as herein shown and described.

7. In a tag-making machine, the combination, with a vertically-movable carriage carrying an upsetting punch, of a transversely-movable carriage provided with a longitudinal slot, of two dies above the slot, a punch held on a 100 sliding bar on the transversely-movable carriage, an elbow-lever for operating the said punch from a shaft operated from the main driving-shaft, and of an inclined track, at the upper end of which an eyelet-receptacle is 115 held, substantially as herein shown and described.

8. In a tag-making machine, the combination, with a vertically-movable carriage carrying the tubular punch P , of the transversely-movable carriage J , provided with the slot J' , and above the slot with a boss or projection, M , in which the dies L^4 and P^2 are held, the vertically-sliding punch L' , held on the transversely-sliding carriage J , an elbow-lever 120 operated from the main shaft, a rod, P' , extending through the tubular punch P , and of a bracket, Q^3 , on the frame, substantially as herein shown and described.

9. In a tag-making machine, the combination, with a frame, of a transversely-sliding carriage carrying dies and a punch, a vertically-sliding carriage carrying a tubular upsetting-punch in which a rod is held to slide vertically, and of

a bracket on the frame of the machine, against which bracket the said rod strikes when the carriage moves downward, whereby the said rod is pushed upward, substantially as herein shown and described.

10. In a tag-making machine, the combination, with the swinging bar S, of the blade S' and the V-shaped blade S² held on the same, and of the pivoted support U, resting on a cushion or spring, W, substantially as herein shown and described.

11. In a tag-making machine, the combination, with the frame, of the fixed blade T, the pivoted bar S, carrying the blades S' S², and the pivoted support U, resting on a rubber cushion, substantially as herein shown and described.

12. In a tag-making machine, the combination, with the frame, of the main driving-shaft, the shaft E, operated from the same, the shaft O, operated from the shaft E, the cam-wheel R on the end of the shaft O, the lever R', acted upon by the cam-wheel, the connecting-rod R², the pivoted bar S, connected with the rod

R², and of the blades S' S² on the bar S, substantially as herein shown and described.

13. In a tag-making machine, the combination, with the frame, of the driving-shaft D, the shaft E, operated from the same, the shaft O, operated from the shaft E, the cam-wheel N' on the shaft O, the elbow-lever N, acted upon by the cam wheel N', the transversely-sliding carriage J, and the vertically-sliding bar L on the same, which bar is operated from the lever N, the punch L', held in the upper end of the bar L, dies held on the carriage J, a vertically-sliding carriage which operates the transversely-sliding carriage, an upsetting-punch on the vertically-sliding carriage, and of an inclined track held on the transversely-sliding carriage, on the upper end of which inclined track a receptacle for eyelets is held, substantially as herein shown and described.

HARMER DENNEY.
